US00D900054S

(12) **United States Design Patent** (10) **Patent No.:** **US D900,054 S**
(45) **Date of Patent:** **** Oct. 27, 2020**

(54) **WRISTBAND LOUDSPEAKER**

(71) Applicant: **Harman International Industries, Incorporated**, Northridge, CA (US)

(72) Inventor: **Hyo Jin Kim**, Shenzhen (CN)

(73) Assignee: **Harman International Industries, Incorporated**, Northridge, CA (US)

(**) Term: **15 Years**

(21) Appl. No.: **29/674,655**

(22) Filed: **Dec. 21, 2018**

(51) LOC (12) Cl. **14-01**

(52) U.S. Cl.

USPC **D14/192; D14/204**

(58) **Field of Classification Search**

(57) **CLAIM**

The ornamental design for a wristband loudspeaker, as shown and described.

DESCRIPTION

FIG. 1 is a perspective view of a wristband loudspeaker, showing the new design;

FIG. 2 is a front view thereof;

FIG. 3 is a rear view thereof;

FIG. 4 is a top plan view thereof;

FIG. 5 is a bottom view thereof;

FIG. 6 is a side elevational view of one side thereof;

FIG. 7 is a side elevational view of the opposite side thereof;

FIG. 8 is a perspective view thereof shown with an illumination effect.

FIG. 9 is a front view of the module illustrated separate from the wristband loudspeaker, the module shown separately for ease of illustration;

FIG. 10 is a rear view of the module of FIG. 9;

FIG. 11 is a top view of the module of FIG. 9;

FIG. 12 is a bottom view of the module of FIG. 9;

FIG. 13 is a side view of one side of the module of FIG. 9; and,

FIG. 14 is a side view of the opposite side of the module of FIG. 9.

In the drawings, the claimed design is defined by the photographic surfaces; the broken lines depict unclaimed environment that is for illustrative purposes only and form no part of the claimed design.

1 Claim, 12 Drawing Sheets
